UNITED STATES PATENT OFFICE.

LOUIS N. CLAYTON, OF TRENTON, NEW JERSEY.

BLACKING-BOX HOLDER.

SPECIFICATION forming part of Letters Patent No. 414,291, dated November 5, 1889.

Application filed December 15, 1888. Serial No. 293,708. (No model.)

To all whom it may concern:

Be it known that I, LOUIS N. CLAYTON, a citizen of the United States, residing at Trenton, in the county of Mercer and State of New Jersey, have invented a new and useful Blacking-Box Holder, of which the following is a specification.

My invention is designed to provide a cheap and convenient article designed to hold firmly a box of blacking while the brush is being applied to the blacking, and by its use avoid the soiling of the hand.

My invention is shown in the accompanying drawings.

In the drawings, Figure 1 is a perspective view of my holder with the box of blacking attached and with a part of the side of the holder and a part of the box and contents broken away, to show more clearly the method of fastening. Fig. 2 is a sectional view of my holder, taken longitudinally, and of the box in position thereon.

In the drawings similar parts are indicated by similar letters of reference.

In Fig. 1, A represents my holder, and B the box. At the end of the holder A is a sharpened point of metal C. Upon the upper side of the holder I place a rack D, composed of the loop or staple D' and the bent central spring D². Beneath the holder is shown the fastening-lever E. This lever is pivoted in the holder, and held in place by the catch F.

In Fig. 2, E represents this lever pivoted at E' and curved and pointed at its upper end E².

F represents the catch which serves to hold 35 the lever firmly in place.

The operation of my holder is this: Desiring to fasten a box of shoe or other blacking upon the holder A, I lower the lever E until it is at about right angles to the plane of the 40 holder A. This brings the curved point E² of the lever E standing upward from the holder. Having previously with the sharp point C thrust a hole through the bottom of the box B, I place this box upon the upper curved end 45 E² of the lever E. I then bring the lever up until it engages with the catch F, which holds it in position, and the curved end E², binding against the bottom of the box B, holds the box firmly in position on the holder A. The rack 50 D is used for holding a cord or slip of paper, to prevent the soiling of the hand by the spattering of the blacking when the brush is being charged in the box B.

What I claim as my invention, and desire 55 to secure by Letters Patent, is—

1. A blacking-box holder composed of the holder A, having pivoted lever E, with curved end E² and catch F, as shown and described.
2. A blacking-box holder composed of the 60 holder A, provided with the point C, and bearing the rack D, and carrying the pivoted lever E, with its catch F, as shown and described.

LOUIS N. CLAYTON.
